UNITED STATES PATENT OFFICE.

WILLIAM C. FERGUSON, OF CHAMPAIGN, ILLINOIS.

BUILDING-BLOCK.

1,190,226.

Specification of Letters Patent.

Patented July 4, 1916.

Application filed March 18, 1915. Serial No. 15,232.

To all whom it may concern:

Be it known that I, WILLIAM CLARENCE FERGUSON, a citizen of the United States, residing at Champaign, State of Illinois, have 5 invented certain new and useful Improvements in Building-Blocks, of which the following is the specification.

This invention relates to building blocks and particularly refers to that type of block 10 adapted to be used in the construction of sewers, water conduits and the like, and the objects of the invention are to facilitate the assembling and particularly the securing of such blocks in position, to lock the adjacent 15 blocks together and in place so that the sewer or water conduit will withstand internal pressure together with extreme external weight, and it consists essentially in the improved construction of the blocks and 20 particularly the locking means.

With these objects in view, the invention consists in the arrangement, combination and construction of parts hereinafter described and particularly pointed out in the 25 claims, it being understood, however, that I do not intend to limit myself to the details of the construction or arrangement of parts.

The invention is illustrated in the accompanying drawings in which—

30 Figure 1 shows a cross sectional elevation of a sewer section constructed in accordance with this invention. Fig. 2 shows the method of assembling the parts of Fig. 1. Fig. 3 shows a modification of Fig. 1. Fig. 35 4 shows the method of assembling the parts of Fig. 3. Fig. 5 shows a still further modified form of locking means. Fig. 6 shows the method of assembling the parts of Fig. 5.

In the drawings the numeral 1 indicates 40 a hollow outer block used in the construction of sewers. 2 indicates lining plates used in conjunction with the outer block 1 in the construction of sewers. In this construction the blocks and plates may be given any desired 45 degree of curvature but any other construction of these blocks and plates could be made without curvature without departing from the spirit of this invention. In the block 1 is provided a longitudinal groove 50 3 having walls 4 and a top 5. The plates 2 are provided with longitudinal edge ribs 6. The adjacent ribs 6 are adapted to freely enter the groove 3 but in such a manner that a space is left between the walls of the

groove and the ribs. The ribs may be spaced 55 apart as in Figs. 3 and 4 or they may abut as in Fig. 1.

7 indicates a lateral space extending into the block 1 from the top of the groove 3.

8 indicates a similar space but extending 60 oppositely into the ribs 6.

9 indicates a clip made of metal or any suitable material having downwardly and inwardly bent fingers 10 and horizontally extending fingers 11. 65

In Fig. 3 the construction is somewhat similar in that the same lateral spaces 7 are provided in the groove 3 but the spaces 8 are missing from the ribs on the plates 2. Instead V-shaped recesses or grooves 13 are 70 provided on the adjacent faces of ribs 12 and thereabove the adjacent faces of these ribs are cut away as at 14. The locking member in this instance is different from the clip 9 in Fig. 1 in that it is composed of a 75 diamond-shaped, square or round portion 15 adapted to be inserted in the grooves 13 between the ribs 12 and to have a stem or neck portion 16 adapted to extend upwardly past the cutaway faces 14 of the ribs 12. 80 This neck portion 16 terminates in fingers 11 adapted to enter the spaces 7 when the parts are assembled similar to Fig. 1.

In Fig. 5 the walls of the recess 3, instead of being straight as in Fig. 1 may be 85 grooved or channeled as shown at 17. The walls of the ribs adjacent to the walls 17 are oppositely channeled as at 18.

19 represents a deformable member in the groove 3 which will be deformed by the 90 insertion of the ribs 20 into groove 3 until it expands or changes its shape to conform to the grooves 17 and 18 as shown in Fig. 5.

In assembling the parts of Fig. 1 the clip 9 is applied to the adjacent ribs 6 and the 95 fingers 10 are bent slightly downward and the fingers 11 bent slightly upward as shown in Fig. 2. The ribs 6 of the plates 2 are then pressed upwardly into groove 3 until the plates 2 and the block 1 abut. 100 During this operation the walls 4 of the groove bend the fingers 10 downward and press their inward projections into grooves 8, and, the fingers 11 striking the top of the groove 5 will be bent toward the horizontal until when the operation is finished their extremities will project into and fill the space 7 as shown in Fig. 1. When the

fingers 10 and 11 of the clip are all in place as shown in Fig. 1 it can be seen that the ribs 6 are securely locked together by the fingers 10 and they are securely locked into 5 the groove 3 by means of the fingers 11. These clips may be placed at intervals along the ribs 6 or they may be continuous.

The action of the locking member in Figs. 3 and 4 is somewhat similar to that just 10 described with the exceptions that no means are provided for locking the ribs together. This modification only shows means for locking them in the groove. The portion 15 may be of such a size as to force the ribs 12 apart and make them fit tightly in the groove 3. As the adjacent ribs with the member 15 between them, are forced into the groove 3, the fingers 11 are bent horizontally until when the ribs are seated as 20 in Fig. 3 they extend into the space 7 and the ribs are thereby locked in the groove. The locking members herein described may be made of metal or any other suitable material and it is entirely within the scope of 25 this invention to apply them in a molten condition as well as in the manner that has been set forth.

In the modification shown in Figs. 5 and 6, the locking member is entirely different 30 in shape from the others but it is similar to them in being deformed into operative position by the insertion of the ribs into the groove. In assembling these parts the deformable members are placed between the 35 ribs and the walls of the groove as shown in Fig. 6. The members 19 in this particular case are hollow and present in cross section an elongated diamond. The particular shape, however, may be varied as 40 conditions warrant or require. When pressure is applied upwardly upon the ribs, they are pressed into the groove and during this operation the members 19 are deformed so that they become less elongated and wider 45 and fit into and fill the space between the channels 17 and 18 thereby securely locking the ribs into the groove. These members 19 may be continuous and as long as the blocks or they may be short and only

inserted at intervals between the ribs and 50 the blocks.

Having now described my invention, what I claim is:

1. A sewer pipe section comprising an outer block having a longitudinal groove, 55 lining plates having longitudinal ribs along their edges, the ribs of two adjacent plates adapted to freely enter said groove, and pliable means for locking said ribs in said groove applied to said groove by said ribs. 60

2. A method of locking the adjacent ribs of two lining plates into a sewer section block having a groove therein consisting in placing a pliable medium in the groove and deforming the same by pressure of the ribs 65 into the groove until its deformation locks the ribs in the groove.

3. A sewer section comprising a block having a groove in one of its faces, lining plates having longitudinal edge ribs, the adjacent ribs of two plates adapted to freely 70 enter said groove, and pliable means for locking said ribs to each other and into said groove said means being carried by said ribs and rendered effective by the seating 75 of said ribs in said groove.

4. A sewer section comprising a block having a groove in one of its faces, lining plates having longitudinal edge ribs, the adjacent ribs of two plates adapted to freely 80 enter said groove; and means for locking said ribs into said groove comprising finger carrying metallic members, said fingers adapted to be bent into locking position by the insertion of the ribs into said groove. 85

5. A sewer section comprising a block having a groove in one of its faces, lining plates having longitudinal edge ribs, the adjacent ribs of two plates adapted to freely 90 enter said groove, and means for locking said ribs to each other and into said groove comprising finger carrying metallic members, certain of said fingers adapted to be bent over said ribs and certain others to be bent into locking position by the insertion 95 of the ribs into said groove.

W. C. FERGUSON.
